(57) **CLAIM**

I claim the ornamental design for a tubular cat collar cover with piping trim, as shown and described.

DESCRIPTION

FIG. 1 is a perspective view of the tubular cat collar cover with piping trim showing my new design;

FIG. 2 is a top plan view, the bottom plan view being the mirror image thereof;

FIG. 3 is a front elevational view thereof;

FIG. 4 is a rear elevational view thereof;

FIG. 5 is an end elevational view thereof, the opposite end view being the mirror image thereof; and,

FIG. 6 is a perspective view thereof shown in use.

The cat depicted by broken lines in FIG. 6 has been shown for the purpose of illustrating environment that forms no part of the claimed design.

The tubular cat collar cover with piping trim is a sleeve of fabric that is sewn together on the long edge and trimmed with piping. The ends are left open for the purpose of sliding the cover onto a cat's collar.
